Primary Examiner—T. Chase Nelson*Assistant Examiner*—Karen Acker(74) *Attorney, Agent, or Firm*—Baker, Donelson, Bearman, Caldwell & Berkowitz, PC; Lea H. Speed; Peter L. Brewer(57) **CLAIM**

I claim the ornamental design for a support strap, as shown and described.

DESCRIPTION

FIG. 1 provides a perspective view of the support strap.

FIG. 2 shows a top view of the support strap of FIG. 1.

FIG. 3 presents a first side view of the support strap.

FIG. 4 presents a second opposing side view of the support strap.

FIG. 5 is a bottom view thereof.

FIG. 6 provides a rear view thereof; and,

FIG. 7 provides a front view of the support strap.

The releasable ring connectors in the support strap are shown in broken lines and do not form a part of the claimed invention. Likewise, the reinforcing folds in the strap are shown in broken lines and do not form a part of the claimed invention. The support strap is shown wrapped around a tree trunk. The tree trunk is likewise shown in broken lines and forms no part of the claimed invention.
